United States Patent Office.

JAMES DEPEU AND J. DARRAH HALL, OF PEEKSKILL, NEW YORK.

Letters Patent No. 66,309, dated July 2, 1867.

IMPROVED CAR-COUPING.

The Schedule referred to in these Letters Patent and making part of the same.

TO ALL WHOM IT MAY CONCERN:

Be it known that we, JAMES DEPEU and J. DARRAH HALL, of Peekskill, in the county of Westchester, and State of New York, have invented a new and useful improvement in Car-Coupling; and we do hereby declare that the following is a full, clear, and exact description thereof, which will enable others skilled in the art to make and use the same, reference being had to the accompanying drawings, forming part of this specification.

This invention consists in an arrangement of parts whereby two railroad cars may be automatically coupled together in a safe and convenient manner, and uncoupled in the most expeditious manner from the side or platform of the car.

Figure 1 represents the draw-heads of two cars coupled together by our improved method, the view being a vertical section through the line $x-x$ of fig. 2.

Figure 2 is a top or plan view of the coupling, one draw-head being shown in section as through the line $y-y$ of fig. 1.

Similar letters of reference indicate like parts.

A represents the draw-heads; B is the coupling link; C is a pin which holds the back end of the link; D is a weighted lever or catch which is attached to the draw-head by a pivot at a ; E is a vertical catch-pin which passes down from the top of the draw-head and holds the end of the catch D, when the cars are coupled, as seen in fig. 1. E is secured in its place by a small pin which passes through it, the ends of which work in a slot in a collar on the draw-head, as seen in the drawing. To uncouple the cars the pin E is raised, which liberates the link, as when not held by E the weighted end of the lever or catch D drops down by its own gravity and assumes the position seen in the left-hand draw-head A'. When the cars are to be coupled and are coming together the link will strike the weighted lever or catch D, as it stands and is seen in A', the heavy end of D would be forced up, raising the catch-pin E and passing it where the pin will drop down and catch it as it is seen in the other draw-head. There is one feature in our arrangement which gives it additional novelty, and that is, each draw-head always carries a link, and both links can be used at the same time, if desired. Under ordinary circumstances but one link would be used, as seen in fig. 1, and belonging to A'. The link in the other draw-head would remain as seen, drawn back and held by the coupling-pin C, and resting on the bottom or lower portion of the recess in the draw-head out of the way. The pin C passes through a sleeve marked f, which the link surrounds, as seen plainly at the right hand of fig. 2. e is a shoulder on the pin, which rests upon the top of the sleeve f. When the pin is raised so that the collar is above the draw-head, it may be slipped forward and dropped through the draw-head in another position, as seen in A', fig. 1. This movement carries the link with it, as the link is attached to the sleeve by an eye, as seen. The long slot seen in the top of the draw-head in A', fig. 2, allows the pin to pass from one point to the other without taking it from the sleeve. e are recesses at each end of this slot, upon the bottom of which the shoulder of the pin rests. There is a slot in the bottom of the draw-head which allows the end of the weighted lever D to drop down so that it does not interfere with the entrance of the link when the cars are coupling.

The arrangement of the double link is a great convenience and safeguard. If a link is broken or lost, as frequently happens on trains coupled in the usual way, our coupling always has a link in reserve placed just where it is wanted. In drawing heavy trains a double link is frequently necessary to insure safety. In cases of this kind our coupling is always ready for the emergency.

What we claim as new, and desire to secure by Letters Patent, is—

The sleeve f which holds the link, and the arrangement by which the sleeve and the coupling-pin C are moved longitudinally in the draw-head, substantially as described.

We claim a coupling with coupling-links and sleeve f arranged in each draw-head, substantially as described.

We claim the weighted lever D and the catch-pin E, in combination with the sleeve f and pin C, arranged substantially as set forth.

JAMES DEPEU,
J. DARRAH HALL.
